THERMIONIC GASEOUS DISCHARGE
DEVICE

Percy L. Spencer, West Newton, Mass., assignor,
by mesne assignments, to Raytheon Manufacturing Company, Newton, Mass., a corporation
of Delaware

Application August 4, 1931, Serial No. 555,006

5 Claims. (Cl. 175—363)

This invention relates to a thermionic gaseous discharge device of the type having a thermionic cathode consisting either of a filament or an electron-emitting surface heated by an electrically energized heating element. Such a device may be, for example, a rectifier.

One of the objects of my invention is to increase the efficiency of the device by decreasing the heating current as the load on the device increases.

The foregoing and other objects of my invention will be best understood from the following description of exemplifications thereof, reference being had to the accompanying drawing, wherein:

15 Fig. 1 is a showing partly in diagrammatic form of one embodiment of my invention; and

Fig. 2 shows a modification of the circuit shown in Fig. 1.

In a device such as described above, which operates in the medium of an ionizable gas or vapor, it is necessary, in starting the device, to pass heating current through the heating element of the cathode in order to raise the temperature of the cathode to a temperature at which it emits electrons, and also in the case where a vapor is used, to raise the temperature and consequently the vapor pressure of the vaporizable material to the desired operating point. Such devices are capable of and are usually designed for carrying fairly large amounts of load current. Therefore, when a load is impressed on such a device, the cathode will carry a large amount of load current. This load current is ordinarily sufficient to maintain the temperature of the cathode at the point to which it was raised by the heating element. Therefore, it is no longer necessary to heat the cathode by means of the heating current. If this heating current continues to pass, two disadvantages result: first, the power consumed by the heating current is wasted and results in a decreased overall efficiency of the device; second, the heat liberated by the heating current passes out into the device, and must be dissipated therefrom. Inasmuch as the amount of heat liberated in such a device is ordinarily quite high, the problem of dissipating this heat is a considerable one, and the extra heat which must be dissipated, due to the heating current, increases the difficulty in this respect. In accordance with my invention, I eliminate each of the above difficulties in a simple manner by causing the heating current through the heating element of the cathode to decrease as the load increases.

In Fig. 1, which illustrates diagrammatically an embodiment of my invention, I have illustrat-

ed a rectifier consisting of a hermetically sealed envelope 1 having two reentrant stems 2 and 3 carrying presses 4 and 5 at the inner ends of said stems, respectively. Press 4 has sealed therein an anode lead 6 supporting an anode 7 at one end thereof. This anode preferably consists of carbon. The lead 6 extends through the press 4, and is provided with a conductor 6' affording an exterior electrical connection for the cathode 7. The press 5 supports a cathode 8. While this cathode may be of any type which utilizes a heating element heated by heating current, I have illustrated the form consisting of a hollow cylinder 9 heated by an internal heating filament 10. This cylinder is preferably coated on its outer side 15 with a material such as, for example, barium or strontium oxide, to make it a good emitter of electrons when its temperature is raised to the desired point by the filament 10. The cylinder 9 is supported by a cathode lead 11 sealed in the press 5. The filament 10 is connected at one end to the cylinder 9, and at its opposite end to a filament lead 12 also sealed in the press 5. The leads 11 and 12 extend through the press 5, and are provided at their outer ends with conductors 11' 20 and 12' affording exterior electrical connections for the cylinder 9 and the filament 10. The envelope 1 is evacuated in accordance with the usual practice and provided with a gaseous or vaporous filling which may be, for example, mercury. This 30 mercury vapor is supplied from a body of mercury 14 placed within the envelope 1.

The filament 10 is provided with heating current by means of a transformer 15. This transformer consists of an iron core 16 provided at one 35 point thereof with an adjustable section 17, whereby an adjustable air gap may be interposed in the magnetic circuit formed by said core. The core 16 carries a primary winding 18 which may be energized from some suitable source of alternating current through a switching device indicated at 18'. A secondary winding 19 also placed on the core 16 is connected to the two conductors 12' and 13' for the purpose of furnishing heating current to the filament 10. A load circuit is connected between the anode 7 and the cathode 8, and includes in series, a suitable load device, indicated at 20, the secondary 21 of a power transformer 22, and an auxiliary winding 23 wound 50 on the core 16 of the transformer 15. Connection is made to the cathode through the lead 12' and to the anode through the lead 6'. The power transformer also possesses a primary winding 24 which may be connected to a suitable source of 55

alternating current through a switching device, indicated at 25. The arrangement, as described above, is operated first by closing the switch 18', whereby the transformer 15 is energized. Heating current is supplied through the secondary winding 19 to the filament 10. When the temperature of the cathode 8 has risen to the point at which it emits electrons, and the temperature of the mercury 14 has risen so that the desirable vapor pressure exists within the sealed envelope 4, the switch 25 is closed. The power transformer 22 is thereby energized, and current flows between the cathode 8 and the anode 7 during alternate half cycles. The resulting direct current is utilized in the load device 20. Since all of the load current passes through the cathode 8, considerable heat is liberated at said cathode. The current may divide in any proportion between the cylinder 9 and the filament 10, although the greatest amount will usually flow in the cylinder 9. The amount of heat so liberated is ordinarily sufficient to maintain the temperature of the cathode at the desired point. In order to cause the heating current through the filament 10 supplied from the secondary 19 to decrease under these conditions, the auxiliary winding 23 is placed on the same core 16 as the secondary winding 19. This core is so designed that a load current through the winding 23, which is sufficiently large to maintain the temperature of the cathode 8 at the desired point independently of the heating current furnished from the secondary winding 19, is sufficient to completely saturate the core 16. Under these conditions the leakage flux through the primary winding 18 increases to such a degree that the coupling between the winding 23 and the secondary 19 decreases to a very low value. This results in a corresponding decrease in the amount of heating current flowing in the filament 10. For values of load current less than that sufficient to completely saturate the core 16, there will not be sufficient current flowing in the cathode 8 to keep up its temperature. Thus it is desirable that an appreciable amount of current should flow in the heating filament 10. The transformer 15 automatically accomplishes this result, inasmuch as the current supplied by the secondary 19 is a maximum under no load conditions and gradually approaches a minimum as the flux through the core 16 approaches saturation value, due to the load current flowing in the auxiliary winding 23. The constants of the system are preferably chosen so that the amount of heat liberated at the cathode remains substantially constant for practically all values of load currents.

In order to control the value of load current at which the secondary 16 becomes saturated, some suitable regulating means is provided. This may be, for example, the adjustable section 17 included in the magnetic circuit of the core 16. By moving the section 17 outwardly, thereby increasing the air gap interposed in the magnetic circuit of the transformer 15, a higher load current must pass through the auxiliary winding 23 before the core 16 becomes saturated. By moving the section 17 inwardly, thereby decreasing the interposed air gap, the value of load current in 23 at which the secondary 16 becomes saturated decreases.

When the current through the filament 10 has fallen below a certain value, it may be desirable to open the circuit of said filament in-

asmuch as the load current under such condition is sufficient to maintain the temperature of the cathode at the desired operating point. A manual switch, such as that indicated at 26, may be provided to accomplish this result. It is also possible to cause the opening of the filament circuit to occur automatically, and such an arrangement is illustrated in Fig. 2. In that figure a relay 27 is placed in series with the filament circuit, and is operated by a voltage coil 28 connected across the terminals of the secondary coil 19. When the coil 28 operates the relay 27, the filament circuit is completed across the two contacts 29 and 30. When the switch 18' is initially closed, the voltage across the coil 19 is at a maximum and the relay 28 operates to complete the filament circuit. As the load from the coil 23, however, increases, not only the current through the coil 19 decreases but also the voltage across said coil decreases until at a certain predetermined value the coil 28 releases the relay 27, opening the filament circuit. If at any subsequent time the amount of the load falls to such a value that the load current is insufficient to keep up the temperature of the cathode, the constants of the circuit are so chosen that the voltage across the terminals of the secondary 19 will rise to a point sufficiently high to operate the relay 27, whereupon the filament circuit is again closed and an amount of current sufficient to maintain the temperature of the cathode flows through the filament 10.

This invention is not limited to the particular details of construction, materials or processes described above, as many equivalents will suggest themselves to those skilled in the art. It is accordingly desired that the appended claims be given a broad interpretation commensurate with the scope of the invention within the art.

What is claimed is:

1. A gaseous discharge device comprising an anode, a thermionic cathode of the type heated by an electrical current, a transformer including a primary winding adapted to be connected to a source of alternating current, a secondary winding magnetically coupled to said primary winding and connected to said cathode to supply heating current thereto, means responsive to the current passing between said anode and cathode to decrease the magnetic coupling between said primary and secondary windings as said anode-cathode current increases, and means responsive to the voltage across said secondary to open the connection between said secondary and said cathode when said voltage falls below a predetermined minimum.

2. A gaseous discharge device comprising an anode, a thermionic cathode of the type heated by an electrical current, a source of current connected to said cathode to supply heating current thereto, means responsive to the current passing between said anode and cathode to decrease the potential of said source as said anode-cathode current increases, and means responsive to the potential of said source to open the connection between said source and said cathode when said potential falls below a predetermined minimum.

3. A gaseous discharge device comprising an anode, a thermionic cathode of the type heated by an electrical current, a transformer including a primary winding adapted to be connected to a source of alternating current, a secondary winding magnetically coupled to said primary winding and connected to said cathode to supply heating

current thereto, means responsive to the current passing between said anode and cathode for decreasing the voltage across said secondary winding as said anode-cathode current increases, and means responsive to the voltage across said secondary to open the connection between said secondary and said cathode when said voltage falls below a predetermined minimum.

4. An electrical space discharge device comprising an anode, a thermionic cathode of the type heated by an electrical current, means for heating said cathode, a source of current connected to said heating means to supply heating current thereto, means to vary the potential applied to said heating means as said anode-cathode current varies, and means responsive to said poten-

tial to open the connection between said source and said heating means when said potential falls below a predetermined minimum.

5. An electrical space discharge device comprising an anode, a thermionic cathode of the type heated by an electrical current, means for heating said cathode, a source of current connected to said heating means to supply heating current thereto, means to vary the potential applied to said heating means as said anode-cathode current varies, and means responsive to said potential to open and close the connection between said source and said heating means when said potential falls below and rises above a predetermined value, respectively. 15
